(57) **CLAIM**

The ornamental design for a watch band, as shown and described.

DESCRIPTION

FIG. 1 is a rear perspective view of a watch band according to a first embodiment of my new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded view thereof;

FIG. 10 is another perspective view thereof showing the watch band in an environment in which it may be used;

FIG. 11 is an enlarged view of encircled portion 11 of FIG. 9;

FIG. 12 is a rear perspective view of a watch band shown without the environmental subject matter in use;

FIG. 13 is a front perspective view thereof;

FIG. 14 is a front view thereof;

FIG. 15 is a rear view thereof;

FIG. 16 is a left side view thereof;

FIG. 17 is a right side view thereof;

FIG. 18 is a top view thereof;

FIG. 19 is a bottom view thereof;

FIG. 20 is an exploded view thereof;

FIG. 21 is another perspective view thereof showing the watch band in an environment in which it may be used; and, FIG. 22 is an enlarged view of encircled portion 22 of FIG. 20.

The evenly broken lines shown in the drawings are included for the purpose of illustrating both parts of the article as well as exemplary environmental subject matter. The dot-dash broken lines represent the designation of enlargement views. None of the broken lines form part of the claimed design.

1 Claim, 22 Drawing Sheets
